UNITED STATES PATENT OFFICE

HARRISON H. BOYCE, OF JERICHO, NEW YORK

RADIATOR-CAP-SECURING DEVICE

Application filed March 21, 1927. Serial No. 176,898.

One of the objects of this invention is to provide an improved locking device for a radiator closure device.

Another object of this invention is to provide a radiator closure lock operated by rotating a device for indicating the condition within a radiator.

Another object of this invention is to provide a locking device for a radiator filler spout closure, the locking of which forces the closure device against the end of the filler spout.

Another object of the invention is to provide a locking radiator cap closure in which all the locking parts are concealed within the radiator filling neck so that the appearance of the outside of the filling neck and cap is not changed and there are no protruding parts to become broken.

Various other objects and advantages will appear as the description of the invention proceeds.

Referring to the drawings in which I have shown what I now consider the preferred embodiment of my invention.

Fig. 1 is a view partly in section showing my improved locking device applied to a radiator filler spout closure device.

Fig. 2 is a central cross-section of my locking device applied to a radiator filler spout closure device taken at right angles to Fig. 1.

Fig. 3 is a cross-sectional view on the line 3—3 of Fig. 1.

Fig. 4 is a cross-sectional view taken on line 4—4 of Fig. 1.

Fig. 5 is a detail of the gripping disks.

Figs. 6 and 7 are details of the gripping disks operating jam nut.

I have designated the radiator filler spout closure device by the numeral 1 in Figs. 1 and 2, and the radiator filler spout as 2. The closure device 1 is formed with an annular flange 3 extending downwardly from the periphery thereof and with a cylindrical portion 4 extending downwardly within and spaced from the flange 3. When the closure cap or device 1 is in place in closing position on the filler spout 2, the spout projects into the annular space between the cylindrical

projection 4 and the flange 3 and seats against a gasket 5, as shown in Figs. 1 and 2.

A rectangular aperture 6 extends axially of the cylindrical projection 4 from the lower end thereof to a point within the body of the closure device 1. A circular recess 1' is formed in the upper surface of the closure device 1 in axial alignment with the aperture 6 and a circular aperture 7 extends in axial alignment with and connects the recess 1' and the aperture 6.

A device 8 for indicating the condition within an automobile radiator is positioned with its stem 8' extending through the aperture 7 and the aperture 6. The stem is provided with a shoulder 9 which seats in the recess 1' and is held against outward movement by a member 10 secured to the upper surface of the closure device 1 by the screws 11.

Threads 12 are formed on the stem 8' of the indicating device 8 within aperture 6. A nut 13 is mounted on this thread portion of the stem 8' and is provided with a rectangular portion 14 cooperating with the rectangular aperture 6 to prevent the nut from turning. By rotating the indicating device 8, the nut or element 13 will be moved along the stem 8' in the aperture 6 by the threads 12. The nut 13 is tapered towards its lower end, as shown in Figures 1, 2, 6 and 7 for a purpose which will presently be described.

The cylindrical projection 4 is provided with radial slots 15 in the sides thereof and in each of these slots a serrated gripping disk 16 is mounted on a rod 17 as shown in Figs. 1 and 2.

These gripping disks 16 do not fit snugly on the rods 17 but are provided with central openings larger than the rods 17 as considerable play is desirable between the gripping disks and the rods. These gripping disks extend into the aperture 6 and are engaged by the sloping surface of the nut 13 as the latter is moved downward by turning the indicating device 8. The downward movement of the nut 13 forces the gripping disks 16 outward into engagement with the inner surface of the filler spout 2 where the serrated edges are projected into the metal of the

100

filling neck and at the same time the downward movement of the nut 13 rotates the disks around the rods 17 to draw the closure device downward, thus firmly seating the same 5 against the upper end of the filler spout.

The closure portion may be positioned on the filling neck so that in gripping position, the indicator 8 is in the proper position for reading from the driver's seat.

10 It will thus be seen that I have provided a radiator neck closure or cap which may be quickly removed from or secured to the radiator filling neck, and securely fastened in place, and which will cooperate with the ordinary filling spout or neck without the necessity for providing a hinge means or other projection on the filling neck.

20 Various changes in the construction of the embodiment illustrated in the drawings may be made without departing from the spirit of the invention, and I do not therefore desire to limit myself to the specific construction shown and described, but to interpret the invention broadly within the scope of the 25 appended claims.

What I claim as my invention is:

1. In a device of the class described, a radiator filler spout, a closure device therefor, a plurality of rotatable members mounted on 30 said closure device adjacent the inner surface of the filler spout and forced into engagement with the filler spout and rotated to draw the closure device into closed position by rotation of a device for indicating the 35 condition within the radiator mounted on said closure device.

2. In combination with a radiator closure cap, a device for indicating the condition within a radiator mounted on said closure 40 cap for rotation without translation and locking means rotatable and translatable by rotation of said device.

3. In a device of the class described, a radiator filler spout, a closure cap therefor, 45 a device for indicating the thermal condition of the interior of the radiator mounted on said cap, a non-rotatable member for the cap and connected to be operated by said indicating device, and a plurality of separate 50 rotatable members contacting with the aforesaid member for securing the closure cap to the filler spout and releasing said cap therefrom.

4. In combination with a radiator closure 55 cap for a filler spout, a member mounted on said cap and capable of rotation without translation, said member being adapted for external rotation, a screw threaded stem thereon and extending internally of said cap, 60 an internal member translatable by rotation of said first member, a plurality of eccentrically pivoted gripping discs operated by the second member and adapted to be forced into and out of contact with said filler spout 65 by external rotation of said first member.

5. In combination with the filler spout of a radiator, a closure cap for said spout, a device on the exterior of the cap for indicating the thermal condition of the interior of the radiator, said device having a part projecting from the cap into the spout, an element engaged by said part to be moved bodily but held against rotation, and means mounted on the cap to be disposed on the inside of the spout and movable bodily in an outward direction by said element to hold the closure cap in place on the spout.

6. In combination with the filler spout of a radiator, a closure cap therefor, a device carried upon the outside of the cap for indicating the thermal condition of the inside of the radiator, said device having a part projecting from the cap to the inside of the spout, an element engaged by said part to be moved bodily but held against rotation, and rotatable means on the cap to be turned by said element to secure the cap in place on the spout.

7. In combination with the filler spout of a radiator, a closure cap therefor, a device on the outside of the cap for indicating the thermal condition of the interior of the radiator, said device having a part projecting from the cap to the inside of the spout, an element engaged by said part to be moved bodily but held against rotation, and rotatable means on the cap mounted to be turned and moved bodily by said element into engagement with the inside of the spout to secure the closure cap thereon.

In testimony whereof I have affixed my signature to this specification.
